UNITED STATES PATENT OFFICE.

JOHN D. RIPSON, OF SHELBOURNE FALLS, MASSACHUSETTS, ASSIGNOR OF ONE-HALF TO LEWIS J. BIRD, OF BOSTON, MASSACHUSETTS.

CASKET.

SPECIFICATION forming part of Letters Patent No. 739,509, dated September 22, 1903.

Application filed September 29, 1902. Serial No. 125,192. (No model.)

To all whom it may concern:

Be it known that I, JOHN D. RIPSON, a citizen of the United States, residing at Shelburne Falls, in the county of Franklin and State of Massachusetts, have invented an Improvement in Caskets, of which the following description, in connection with the accompanying drawings, is a specification, like characters on the drawings representing like parts.

10 The invention to be hereinafter described relates to caskets, and has for its object the production of a simple and inexpensive structure wherein the body of the casket is composed of wood and the curved ends of metal, preferably each of single pieces properly molded into shape; and with these general objects in view the invention consists of the parts and combinations, as will be hereinafter described, and definitely pointed out in the 20 claims.

Figure 1, in side elevation, shows a closed casket embodying my invention; Fig. 2, a cross-section in the line *x*, Fig. 1; Fig. 3, a partial longitudinal section through the body 25 of the casket at one end. Fig. 4 shows parts of the lid upturned, and Fig. 5 shows in plan view one end of the body of the casket with the lid removed.

The casket-body herein represented comprises a bottom board *a*, two sides *b*, and two molded ends *c*, said ends having suitable ornamental ribs *d*, *d*. The end pieces, preferably of metal, have imparted to them the shape desired by the use of dies in a machine substantially such as described in United States Patent No. 674,647, granted May 21, 1901. The wooden sides *b* of the casket at the upper edges of their opposite ends have secured to them by nails or screws 30 a rim *e*, preferably of bent wood, the shape of the rim being of the shape it is desired to impart to the end of the casket. The curve of the rim may be more or less. The molded end pieces *c* will be composed, preferably, of metal bent 35 or formed into shape in a die. The upper end of each end piece is united to a rim *e*, as shown in Fig. 3, by suitable fastenings. The lower edge of each end piece *c* is shaped to form a bead *d'*, having at its lower end an in- 40 turned flange (see Fig. 3) that embraces the

curved end of the bottom *a*, said flange underlying said bottom.

Nails or other fastenings *d* may be driven through suitable holes in said flange and into the bottom of the casket, thus connecting the 55 lower edge of the end piece with the bottom of the casket. The external shape of the lower part *d'* of each end piece is of a shape to accord with the wooden molding *f*, applied to the lower edge of the side pieces *b*. The 60 edge 2 of each curved end is overlapped on the end of a side piece *b* and is secured thereto by suitable fastenings *g*, which may be screws or nails, and that the outer side of each end piece shall be flush with the sides of 65 the side pieces *b*. I have cut away (see Figs. 1 and 5) the outer face of the side pieces to leave a shoulder 4, the depth of the shoulder being equal to the thickness of the metal of the end piece. The side pieces *b* are pro- 70 vided, preferably, with wooden ribs *g* of the shape of the metallic ribs *d*, *d'* of the end piece.

A casket constructed, as described, of wood and metal is light in weight and may consequently be handled easily, and it is cheap to construct, the cost of the production of the casket being reduced, owing to the fact that the end pieces are molded to shape, thus obviating cutting pieces of wood into small sections, beveling their edges, putting them together, and adding ornamental strips.

The lid is composed of a sheet-metal shell *h*, having an external flange *h'*, filled with a non-metallic frame *m*, *m'*, made in pieces and 85 preferably of wood, the parts *m'* being bent or worked out to present a curve, as best represented in Fig. 4. The lid and body are adapted to be united by suitable fastenings *n*.

The chief expense in the labor of producing 90 a casket with curved ends lies in the fitting together of the wood constituting the ends.

I consider as within the scope of my invention the use of a molded end piece of any material, whether of metal or pulp.

Having fully described my invention, what I claim as new, and desire to secure by Letters Patent, is—

1. In a casket, a body formed of wooden sides and having metal ends, each of said 100

ends being formed of a single metallic sheet, a wooden rim extending from the sides above the metal ends, and a metallic lid having a non-metallic frame to form a non-metallic continuous contact between the lid and top of the casket-body.

2. In a casket, a body formed of wooden sides and metal ends, each of said ends being formed of a single metallic sheet, a wooden ¹⁵ rim extending from the ends of the sides above the metal ends, and a metallic shell-

like lid having an external flange, and a non-metallic frame filling said flange to thereby form a non-metallic continuous contact between the lid and top of casket-body.

In testimony whereof I have signed my name to this specification in the presence of two subscribing witnesses.

JOHN D. RIPSON.
